AROMATIZATION OF STRAIGHT RUN NAPHTHENIC GASOLINES

Ivor Gray Nixon, The Hague, Netherlands, assignor to Shell Development Company, New York, N. Y., a corporation of Delaware

Application August 23, 1955, Serial No. 529,986

Claims priority, application Netherlands October 24, 1951

4 Claims. (Cl. 196—50)

The process of this invention involves the treatment of selected fractions of straight run gasoline with added normal pentane with a platinum catalyst under hydrogen pressure.

REFORMING

It is well known that various gasolines having poor anti-knock characteristics can be improved by a catalytic reforming treatment. In the usual catalytic reforming process the gasoline is passed in vapor phase in contact with one of a number of dehydrogenation type reforming catalysts such for example as molybdenum oxide supported on an alumina carrier. The operation is usually carried out in the presence of added hydrogen. In this process, the main improvement is due to dehydrogenation of cyclohexane homologues to the corresponding aromatic hydrocarbons. Also, if the hydrogen pressure is not too high, some minor amount of aromatic hydrocarbons is produced from paraffin hydrocarbons by dehydrocyclization. The improvement in anti-knock properties obtained by these processes increases with increasing severity of the treating conditions until the available hydroaromatic naphthenes are substantially completely converted to aromatic hydrocarbons. The F-2 octane number of the product at this point is generally between 70 and 80. A further improvement in octane number may be obtained by increasing the severity of the treating conditions but this further increase is obtained largely by concentration of the aromatic hydrocarbons already formed through cracking out the less refractory non-aromatic hydrocarbons; such further improvement is, therefore, accompanied by a large loss in yield of liquid product. In commercial practice an 80% yield of a product of about 80 F-2 octane number is considered to be about the upper limit for economical operation. The high octane numbers obtainable by this process are only possible because the process is regenerative, i. e., the catalyst is regenerated after each short period of use. If it is desired to operate in a non-regenerative manner, relatively mild conditions must be used and the attainable improvement is less. By careful fractionation of the product a fraction suitable for use as aviation base stock can be obtained but the yield is poor. A similar product can, of course, be obtained by severe thermal reforming followed by fractionation but the yield is so low that the process is clearly of no practical interest under normal conditions.

PLATFORMING

Recently a reforming process known as platforming has come into use for reforming motor gasolines. In this process gasolines of poor anti-knock characteristics are improved by treatment in the vapor phase and in the presence of hydrogen under pressure with a catalyst consisting of a cracking catalyst promoted with platinum. Aside from the totally different catalyst used, this process differs from the previous reforming process in that it is non-regenerative, i. e., a single charge of the catalyst is used continuously over an extended period of time without regeneration. The catalyst is, therefore, employed in the form of one or more fixed beds through which the hydrocarbons and hydrogen are continuously passed.

2

The catalysts and conditions applicable in this type of operation are described in U. S. Patents No. 2,478,916; 2,479,110; 2,550,531; and 2,602,772 to which reference is made for such particulars. In spite of the fact that cracking is one of the major reactions involved, the yield of liquid product at moderate levels of reforming is somewhat better than attainable with previous processes. Also, in this process isomerization plays a more important role than in previous reforming processes; consequently, the naphthenic hydrocarbons having C₅-rings, e. g., methyl-cyclopentane homologues, which are usually present in appreciable concentrations, are likewise converted to a substantial extent to aromatic hydrocarbons. Also, some of the normal paraffins are isomerized to isoparaffins and this contributes to a minor extent to the improvement.

While platforming has been rather broadly described it is limited in practical application to the treatment of certain feed stocks. This is due to the nature of the reactions which are known to take place. On the one hand, the final boiling point of the feed must not be too high since higher boiling materials tend to coke the catalyst. A final boiling point around the end point of motor gasoline is generally considered about the maximum. On the other hand, the process is most amenable to the higher boiling gasoline constituents. It is therefore generally applied to the high boiling fraction of the gasoline. This is due largely to two factors. The first is that in platforming hydrocracking is one of the most important reactions. When treating 200–400° F. naphtha this hydrocracking leads to the production of high octane components which still boil in the gasoline range and therefore tend to increase the volumetric yield. If lower boiling fractions are treated or included in the feed this hydrocracking leads to the production of materials which boil below gasoline or in the lighter fraction thereof and must be removed to reduce the volatility to the usual range thereby considerably decreasing the volumetric yield. The second is that the improvement in the octane number which may be obtained by platforming sharply declines as the boiling range of the feed is lowered so that a point is soon reached where the minor improvement is insufficient to justify the considerable cost of the platforming operation.

In motor gasoline production it is therefore the practice to platform only the high boiling portion of straight run gasoline boiling between about 200–400° F. In the production of aviation gasoline, which has a lower boiling range than motor gasoline, a fraction of somewhat lower boiling range is treated, e. g., 185–270° F. In either case it is considered undesirable to include hydrocarbons boiling below hexanes and it is therefore the practice to top the straight run gasoline to remove all such material boiling below at least about 140° F. Thus, for example Fulton (Petroleum Refiner, vol. 29, pp. 109–112 (1935)) describes the platforming of various natural gasoline fractions and states that platforming is useful only for the treatment of the "hexanes plus" material and does not apply to the treatment of butanes and pentanes.

The present practice of excluding pentane in the platforming of straight run naphthenic gasoline fractions is based on the following considerations. Pentane, since it contains only 5 carbon atoms, cannot be converted by dehydrogenation or dehydrocyclization to any aromatic hydrocarbon. Hydrocracking is an important reaction in platforming and the catalyst is consequently compounded to produce substantial hydrocracking. The hydrocracking of pentane can lead only to the production of undesirable gases, to lowering of the volumetric yield, and to consumption of valuable hydrogen. The pentane present in straight run distillates is not pure normal pentane but a mixture of normal pentane and isopentane. The only advantage which could be expected by including

pentane would therefore be the small amount of isomerization of normal pentane to isopentane which would take place under the platforming conditions. This could not increase the normal pentane to isopentane ratio to much above 1:1 (the thermodynamic equilibrium between these compounds under the platforming conditions). The F-2-0 octane number of the treated C₅ fraction therefore would be less than about 76

$$\left(\text{i. e. } \frac{90+62}{2} \right)$$

which is lower than the octane number of the higher boiling portion of the platformate. Its presence would therefore tend to lower the octane number of the total product.

The exclusion of lower boiling straight run components, and especially pentane, from the platforming feed is based primarily on the above reasons. Experimental runs using straight run feeds of initial cut-point to include the small amounts of normally occurring pentanes could not be expected to show any beneficial results for the above mentioned reasons and also because the pentane content of such feeds would not amount to more than about 7%.

ADDITION OF PENTANE

Contrary to the belief and teachings hitherto advanced regarding the desirability of excluding pentane in the platforming feed, it has now been found that the inclusion of sizeable amounts of pentane has a totally unexpected beneficial effect. Thus, it has been found that in the presence of sizeable amounts of added pentane the efficiency of conversion of the naphthalenes to aromatics (which is the chief octane-raising reaction in the process) is appreciably increased. It was at one time thought that this improvement was due to the relatively high heat carrying capacity of the added normal pentane which acted as a diluent and possibly also to a small extent by the small heat of the limited isomerization of part of the pentane, which isomerization is slightly exothermic and is known to take place.

Thus, as pointed out, when the reforming operation is carried out with the mentioned acid platinum catalyst, the C₅-ring naphthalenes which are normally present in about equal amounts with the C₆-ring naphthalenes are largely converted to aromatics by dehydroisomerization. The total reaction is, therefore, quite endothermic. It is, in fact, so endothermic that it is difficult to carry out the process without a temperature drop in the catalyst bed. The major amount of the endothermic heat supplied must be supplied by preheating the reactant feed stream. However, the maximum temperature at which the material can be preheated without causing excessive thermal cracking and/or excessive hydrocracking in the forepart of the catalyst bed is strictly limited. In normal operation with the preferred and generally used adiabatic reactors the temperature drop through the catalyst bed is usually over 50° C., and may be as much as 110° C. or more. (See British Patent No. 662,002.)

The main desired reaction is the conversion of the naphthenic hydrocarbons in the feed to aromatic hydrocarbons and this is an equilibrium limited reaction which is influenced by the temperature. The maximum degree of this conversion is, therefore, limited by the equi-

librium at the temperature of the reactor effluent. The effect of a large temperature drop in the reaction zone is to limit the maximum possible conversion to a point below that corresponding to the average reaction temperature. That this effect is larger than might be expected will be seen from the equilibrium curves shown in the graph in the accompanying drawing.

Figure I of the drawing is a graph showing the equilibrium conversions of cyclohexane and methylcyclopentane to benzene plotted against the temperature at a pressure of 30 atmospheres and a hydrogen-to-hydrocarbon mole ratio of 3. The curves are shifted toward the right if the pressure is increased and are shifted downward slightly if the hydrogen-to-hydrocarbon mole ratio is increased. The curves for the equilibrium conversions of the C₇ and C₈ naphthalenes are not identical but from the limited data available, they are of similar shape and relative positions.

Referring to Figure I, it will be noted that under the moderate pressure of 30 atmospheres, and with the low hydrogen-to-hydrocarbon mole ratio of 3 it is possible to obtain over 90% conversion of the cyclohexane at a temperature of 475° C. However, the maximum possible conversion of the methylcyclopentane is less than 60%. Such conversions, if attainable, would not be bad. However, if a temperature drop of 50° C. takes place in the catalyst bed, the exit temperature is 425° C. and at this temperature it is seen that the maximum possible conversions are only 53% and 13%, respectively. The usual means for overcoming this disadvantage is to reheat the product back to a high temperature and retreat it. In the second treatment, the temperature drop is less and, consequently, a higher outlet temperature with a higher limiting equilibrium is possible. Even two such treatments are usually not sufficient to obtain a really efficient conversion and in commercial practice three and often four such treatments are normally used.

If appreciable amounts of normal pentane are added to the feed the temperature drop, although still appreciable will be less and, as will be seen from the curves in the graph, this could result in a more favorable limiting equilibrium conversion.

The above explanation for the improved results appears plausible but it does not fit the facts since the improved conversions have now been obtained under carefully controlled temperature conditions where this heat effect is negligible. Thus, for some unexplained reason the inclusion of appreciable amounts of added pentane results in increased conversion and conversion efficiency, particularly with respect to the C₅-ring aromatic precursors, even under carefully controlled temperature conditions and even at the same base feed throughput rate (hence increased liquid hourly space velocity).

This is illustrated by the data in the following Tables I, II, and III in which are shown the results obtained in platforming the same feed stock containing different amounts of added normal pentane. In order to show the effect most clearly with the least difficulties and uncertainties due to analytical errors these experiments were carried out with a synthetic feed prepared with relatively pure starting materials. To this base stock various amounts of normal pentane were added to give feeds having the compositions shown in the following Table I.

Table I

Feed	A	B	C
	Pound moles per hundred pounds of feed		
Normal Pentane.....	0.2633 (23% mol)	0.5198 (43% mol)	0.8316 (66% mol)
Methylcyclopentane.....	0.4040	0.3125	0.1996
Methylcyclohexane.....	0.4614	0.3565	0.2271
Methylpentanes.....	0.0116	0.0093	0.0046
Benzene.....	0.0026	0.0013	0.0013
Toluene.....	0.0065	0.0043	0.0033

The platforming of these blends was carried out at a liquid hourly space velocity of 2 with a commercial platforming catalyst and with recycled hydrogen. There were 2 reactors in the series, each provided with means for careful temperature control. The pressures in the reactors were 325 and 275 p. s. i. g. The pertinent results are shown in the following Table II.

Table II

Feed	A	B	C
Concentration of normal pentane, mol percent	23	43	66
Average reactor temperature, °F	847	847	843
Reactor No. 1	817	817	813
Reactor No. 2	877	877	873
H ₂ /feed mol ratio	4.4	3.9	4.0
Equilibrium conversion of MCP, percent	75.2	76.5	75.8
Percent of Equilibrium conversion attained	61.0	71.0	82.0
Mol benzene formed per mol MCP charged	.456	.544	.615

It will be noted that the equilibrium conversion of methylcyclopentane (MCP), which is the most sensitive indicator in this case, is the same within experimental limits in all three cases so that loss of conversion due to an unfavorable equilibrium at lower temperatures is excluded. It will be noted furthermore that the percent of equilibrium conversion obtained, i. e. the percentage approach to the equilibrium, was high in all cases and increased significantly with increasing dilution with pentane. Thus, the mols of benzene formed per mol of methylcyclopentane charged increased from 0.456 to 0.615 or an increase of 33%. The methylcyclohexane was in each case converted substantially completely to toluene. These data show that the improved results are not dependent upon any temperature effect and that they are due primarily to improved conversion of the C₅-ring naphthenes, which, as pointed out, constitute approximately half of the aromatic precursors in the usual feed stocks.

The above results were obtained by operating with a constant total feed space velocity (LHSV=2). This advantage however is still maintained if the space velocity, based on the total feed, is increased so that the same amount of base feed is processed. The corresponding results on this basis (calculated from the same data using previously determined conversions versus space velocity correlation curves) are shown in the following Table III.

Table III

Concentration normal pentane, mol percent	23	43	66
Liquid hourly space velocity	2	2.5	3.5
Conversion MCP to benzene, percent	42	48	52
Relative benzene production rate, weight/time	1.0	1.14	1.24

These data show that by adding sizeable amounts of normal pentane the conversion of the hitherto rather inefficiently converted C₅-ring naphthenes to aromatics is increased significantly at the same reaction temperature without loss of through-put or production capacity. This is a new discovery which is of general application but is particularly important in the production of aviation base stock.

In order to produce aviation base stock of high quality, a narrow boiling straight run fraction is separated for treatment. The cut points should be chosen so that the majority of the useful naphthenes are concentrated. On the other hand, the end point should be low enough to meet the boiling range requirements of the composite containing the isopentane. For the reason stated above, the C₆ hydrocarbons should be excluded as far as practicable. The fraction ca. 85° C. to ca. 130° C. (cut point temperature) is suitable for aviation base stock production. All straight run gasoline fractions of this boiling range are, of course, not suitable. The straight run gasoline fractions should be one in which naphthenic hydrocarbon content is high, preferably at least 50%. The

naphthene content of the fraction is dependent upon the naphthenicity of the petroleum from which it is derived.

The amount of added normal pentane must be considerable. It should be borne in mind that the equilibrium between normal pentane and isopentane is not particularly favorable under the reaction temperature conditions and also that complete conversion to the equilibrium is not usually obtained. The amount of normal pentane required is, therefore, considerably above the normal pentane concentration in the straight run gasoline cuts regardless of their initial boiling point. In general, the amount of normal pentane required to be added is between about 10% and 70% of the narrow boiling fraction to be treated and preferably the amount is between 25% and 70%.

Upon completion of the conversion the normal pentane is removed. The recovered normal pentane is advantageously recycled. On the other hand, it is important that no appreciable amount of isopentane be recycled.

20 The process of the invention will be described in more detail in connection with Figure II of the accompanying drawing which schematically shows a flow diagram of one application of the process for the production of an aviation base stock.

25 Referring to Figure II, a debutanized straight run gasoline derived from a naphthenic petroleum and entering via line 1 is passed to fractionating column C₁. Column C₁ is operated to take overhead all of the pentanes. The overhead product is essentially normal pentane but contains a small amount of isopentane. The bottom product from column C₁ is passed by line 2 to fractionating column C₂. Column C₂ is operated to take overhead all of the hexanes. The overhead product is withdrawn by line 3. The bottom product from column C₂ is passed 30 by line 4 to fractionating column C₃. Column C₃ is operated to take overhead the fraction desired for the production of aviation base stock. As pointed out, the recommended cut points for this fraction are 85° C. and 130° C. The bottom product from column C₃ is withdrawn from the system by line 5.

35 The pentane fraction from column C₁ is combined with an isopentane-rich fraction from line 6, later to be described, and the mixture passed to fractionating column C₄. Column C₄ is operated to separate isopentane from normal pentane. The overhead isopentane fraction is withdrawn by line 7 and combined with the reformed stock as later described. The normal pentane fraction withdrawn by line 8 is combined with the overhead fraction from column C₃.

40 As previously pointed out, the amount of pentane normally occurring in straight run gasolines is not sufficient to supply the needs for the process. Normal pentane or a pentane fraction from an exterior source, e. g., from a straight run gasoline of low naphthenicity is therefore introduced by line 9. The mixture of the selected straight run fraction, the recycled normal pentane, and the normal pentane introduced by line 9, is mixed with recycled hydrogen from line 10 and passed to the platforming unit indicated simply in the figure by the labelled rectangle.

45 In the platforming unit the material is heated to a reaction temperature of about 890° F. and then passed through a bed of catalyst consisting of from about 0.1 to about 0.4% of platinum supported upon a cracking catalyst such as alumina treated with hydrofluoric acid or an equivalent fluorinating agent, or a synthetic silica-alumina composite cracking catalyst. The pressure is normally between about 200 and 700 p. s. i. g. The space velocity, i. e. contact time, is adjusted such that the effluent is substantially at equilibrium for the exit temperature.

50 The vaporous effluent is cooled somewhat to condense the major portion of the normally liquid hydrocarbons and then passed by line 11 to column C₅. The purpose of column C₅ is to separate product gas consisting essentially of hydrogen while retaining all of the isopentane in the bottom product. To

this end cooled higher boiling product from line 12 is passed into the top of column C₅. This cooled higher boiling product passing downward through the column effectively removes isopentane from the overhead product. The product gas consisting essentially of hydrogen is recycled to the platform unit by line 10 as described. The amount of hydrogen thus recycled is generally between about 2 and about 10 moles per mole of hydrocarbon feed to the platforming unit. Any product gas in excess of this amount may be withdrawn by line 13. The bottom product from column C₅ is passed by line 14 and valve 15 to separator 16 which normally operates at a lower pressure than column C₅. Low pressure gas released upon reduction of the pressure is withdrawn by line 17. The liquid product from the separator is passed by line 18 to fractionating column C₆. Column C₆ is operated to take overhead all of the pentanes. The bottom product from column C₆ is a highly aromatic material consisting almost exclusively of C₇ and C₈ hydrocarbons. Part of this cooled product is recycled to column C₅ as described. The remaining part is combined with the overhead fraction from column C₄ consisting substantially of isopentanes. The mixing containing the correct ratio of isopentane to reformed stock to provide the required volatility is withdrawn by line 18 as product aviation base stock. The pentane fraction withdrawn as overhead product from column C₆ is recycled back to column C₄ as described. The volatility of the aviation base stock withdrawn by line 18 depends upon the amount of the isopentane fraction recovered as top product from column C₄. The desired correct amount is obtained by adjusting the amount of normal pentane from an outside source introduced by line 9. In a typical case the 85-130° C. straight run fraction separated had the following composition:

	Percent by weight
Naphthenes	62
Aromatics	3
Paraffins	35

The amount of normal pentane required for the distillate was 35 parts by weight for each 65 parts by weight of the distillate. This mixture was treated with a commercial platforming catalyst at a space rate of 2.5 kg. per liter of catalyst per hour at 430° C. and 30 atmospheres pressure. The amount of hydrogen used was 1000 liters (standard conditions) per kilogram of the hydrocarbon feed. There was no noticeable cracking of the pentanes. The pentanes were separated from the product and separated into normal pentane (55%) and isopentane (45%). The isopentane was blended back with the reformate and was just sufficient to provide the necessary volatility.

I claim as my invention:

1. In the production of gasoline from straight run naphthenic distillates boiling in the gasoline boiling range the improvement which comprises adding to the straight run distillate from 25 to about 70% of normal pentane, reforming the resulting mixture in the presence of added hydrogen with an acid platinum catalyst, and fractionating the resulting product to separate normal pentane.
2. In the production of gasoline from straight run naphthenic distillates boiling in the gasoline boiling range the improvement which comprises removing from the distillate all of the material boiling up through hexane and material boiling above the gasoline boiling range, adding to the remainder from 25 to about 70% of the amount thereof of normal pentane, reforming the resulting mixture in the presence of added hydrogen with an acid platinum catalyst, and fractionating the resulting product to separate normal pentane.
3. In the production of gasoline from straight run naphthenic distillates boiling in the gasoline boiling range the improvement which comprises fractionating the naphthenic distillate to remove therefrom material boiling up through hexane and material boiling above about 130° C. leaving a naphthenic fraction boiling between about 85° C. and 130° C., adding to said naphthenic fraction from 25 to about 70% of the amount thereof of normal pentane, reforming the resulting mixture in the presence of added hydrogen with an acid platinum catalyst and fractionating the resulting product to separate normal pentane.
4. Process according to claim 3 further characterized in that isopentane is separated from the pentanes from the straight run naphthenic distillate and from the pentane recovered from the reformed product, said separation being effected together by fractional distillation whereby the isopentane present in the straight run distillate is recovered with the isopentane from the reformed distillate and the combined isopentane is re-mixed with the depentanized reformed product.
